MAURICE M. KASANOF, OF NEW YORK, N. Y.

DRIER AND STEAMER FOR TUBULAR FABRICS.

Application filed November 21, 1927. Serial No. 234,871.

Tubular knitted or woven fabrics, if made of silk, fibre, cotton or wool, or mixtures of these, are in most cases dyed, bleached or washed. After the operations referred to the fabric is put in an extractor to extract the liquid. Although the liquid is extracted to a considerable extent the fabric still remains moist and requires drying. After the fabric is dried it is necessary to subject it to a steaming process to make it soft and to give the fabric the right finish.

My invention relates more particularly to drying means and to the relation of the drying means to a steaming device, the purpose in view being to effect the drying and steaming of the fabric in one operation and the effecting of a saving in time and labor.

The nature of my invention and its distinguishing features and advantages will clearly appear as the description proceeds.

Reference is to be had to the accompanying drawings forming part of this specification, it being understood that the drawings are merely illustrative of one example of the invention.

Figure 1 is a side elevation of a drier and steamer embodying my invention;

Figure 2 is an enlarged vertical section of the upper portion of the devices comprising the steaming means;

Figure 3 is a vertical section of the intermediate portion of the device given particularly to show the drying means;

Figure 4 is a horizontal section on the lines 4—4 of Figure 2;

Figure 5 is a horizontal section on the lines 5—5 of Figure 3;

Figure 6 is a horizontal section on the lines 6—6 of Figure 2;

Figure 7 is an elevation of the device with the steam drum and bowl and the drying drum or shell omitted, the assemblage as in Figure 7 being adapted for the placing of the fabric on the device; and

Figure 8 is a vertical section of the upper portion of the assemblage shown in Figure 7.

I have shown in the illustrated example of my invention the adaptation of the drying means constituting the present invention to a steaming assemblage forming part of the subject matter of an application for patent filed by me November 4, 1927, Serial No. 231,124. In the steaming assemblage referred

to a steam bowl 10 is provided open at the top for the escape of the steam. Said bowl is closed by a solid disc 11 having a central bore and a nipple 12 on said disc which nipple extends into a steam pipe 13 mounted on a suitable base 14 and supplied with steam through an inlet pipe 113. The pipe 15 rises from the disc 11 or bottom of the bowl 10 at the nipple 13 so that the steam flowing from said nipple 12 will pass into the pipe 15 which is formed with a series of apertures 16 for the escape of the steam. The upper end of the pipe 15 is reduced as at 17 and externally threaded to receive the bottom 18 of a steam dome or drum 19 which is screwed to said reduced terminal 17. Steam dome 19 is filled with steam passing into the same from pipe 15.

The bottom 18 of the steam dome or drum 19 is spaced from the open upper end of the steam bowl 10 by an outlet space 20 therebetween for the ample flow of steam outwardly to contact with the tubular fabric A, indicated in dot-and-dash lines, as said fabric is drawn upwardly over the bowl 10, dome 19 and over a stretcher 21.

The stretching frame 21 is an open frame 80 the sides of which rise from the bottom bar 22 of said frame. A threaded bolt 24 passes through bottom bar 22 at the center and through a disc 25 on the plug 119 forming a closure at the center at the top of the dome 19. 75 Screw bolts 27 pass through disc 25 and into the plug or block 119, as fully disclosed in my above mentioned application.

A stretching ring 30 is provided on the dome 19 and removably held seated upon washer 41. For the removable holding of collar 30 the same is formed with notches 31 at its inner periphery and on the dome 19 are outwardly projecting pins 32 so that the collar may be passed downwardly beneath the horizontal plane of pins 32 and the collar then given a partial turn for the pins to hold said collar in place. The collar 41 rests upon the upwardly directed annular flange 39 on dome 19 and the bottom 18 is clamped by screws 42 100 between said flange 39 and ring 40 on the under side of said bottom 18. Drip pipe 35 leads from the bottom of dome 19 into steam bowl 10 to direct to said bowl the water of condensation from the dome 19. Similarly 105 a drain pipe 36 leads from steam bowl 10 to

carry off the water of condensation. The numeral 37 indicates flange or collar on the steam pipe 13 which is suitably secured to the solid bottom 11 of dome 10.

5 The assemblage above described provides for the free flow of steam to the fabric and in order that the space 20 for the out-flow of the steam may be varied, I provide collars or washers 34 on the reduced end 17 of pipe 13, 10 said collars being employed in suitable number according to the size to be given to space 20.

With steam dome 19 filled with steam the said dome serves to dry the fabric passing over the same when drying is required. The steam escaping through the space 20 does not actually wet the fabric, and in some instances when the fabric is moist from too much steam the dome 19 has the desired drying effect. 20 When drying is not desired the dome 19 is closed against the entrance of steam by employing a plug in the reduced end 17. A plug 135 is also employed to close the lower end of drip pipe 35 when the steam dome 19 is closed 25 against the entrance of steam in order to prevent steam passing into said dome through pipe 35 from the bowl 10.

In accordance with my present invention the drying means includes a cylindrical shell 30 50 which surrounds the steam supply pipe 13 as well as the drain pipe 36. An air inlet pipe 51 leads laterally into shell 50 and is supplied with air under pressure. Said shell 50 is closed by any suitable means at the top and 35 bottom, there being shown a plug formed of half sections 52, see more particularly Figure 6. The shell 50 terminates at the top short of the bottom of the steam bowl 10, the pipes 13 and 36 extending beyond the upper closure 40 elements 52 to a connection with said bowl 10.

Surrounding the shell 50 at any desired point in its height is a perforated drying drum 53, in which shell 50 there are perforations 54 for the escape of heated air to the drum 53. The air escaping from the perforated drum into contact with and passing through the fabric effects the drying of the fabric. The drying drum 53 may rest on a 45 fixed collar 55 on the air tube or shell 50. At the top of said drum 53 is a set screw 56 to bind the drum on the shell 50 at any desired height thereon that will permit air to pass into drum 53 from perforations 54. By loosening the screw 56 the drum 53 may be slipped upwardly and entirely removed from the shell 50 after steam bowl 10 and steam drum 19 have been removed from the upper end of the pipes 13, 36.

With the steam bowl 10, steam drum 19 and 60 drying drum 53 removed from the assemblage, the fabric may be slipped downwardly over the shell 50. In order to facilitate the placing of the tubular fabric over the pipes 13, 36 and shell 50, I provide, as in Figures 7 65 and 8, a dome 57 depending from which is a

75 plug 58 adapted to fit in the upper end of the steam pipe 13, as shown clearly in Figure 8.

In the use of the above described device the fabric having been placed in position, as indicated in dot-and-dash lines in Figures 2 and 3, any remaining moisture in the fabric will be driven off and the fabric made dry by the drying air escaping from the perforations 54 of shell 50 and through the perforations in drum 53.

75 The drying will thus be effected as the fabric is drawn upward over the drum 53. As the fabric passes from the upper end of the shell 50 it is drawn over the bowl 10 and drying drum 19 and is steamed to give it the proper finish. The drying of the fabric and the steaming thereof to produce the desired finish is effected in succession as the fabric is drawn continuously over the drum 53, shell 10 and steam drum 19. The drying action is 85 materially promoted by the described assemblage since the steam pipe 13 and to a lesser degree the drain pipe 36 serve to heat the air passing to shell 50 and drum 53.

80 The numeral 60 indicates a platform or 90 table on which fabric A rests.

I would state furthermore that while the illustrated example constitutes a practical embodiment of my invention, I do not limit myself strictly to the exact details herein illustrated, since, manifestly, the same can be considerably varied without departure from the spirit of the invention as defined in the appended claims.

95 I claim:

100 1. In an assemblage of the class described, steaming means, a shell having an inlet for drying air and perforated, and a perforated drying drum over which the fabric may be drawn, said steaming means being positioned for the fabric to be drawn over the same after 105 passing over the drying drum.

110 2. In an assemblage of the class described, a shell having an inlet for drying air, a steam pipe passing through the shell, a drying drum surrounding the shell below the upper end thereof and adapted to permit an outflow of air to a fabric drawn over the drum, and steaming means communicating with said pipe and located for the fabric to be drawn 115 over the same after passing over the drying drum.

120 3. In an assemblage of the class described, a drying shell having an inlet for drying air and means on the drying shell over which the fabric may be drawn, and a drying drum surrounding the shell, said means permitting the outflow of air to the fabric passing over the drum.

125 4. In an assemblage of the class described, a drying shell having an inlet for drying air, a collar on said shell, a drum resting on said collar, and means detachably holding said drum against displacement on said shell 130 affording an outflow of air for the drying of

the tubular fabric being drawn over the drum.

5. In an assemblage of the class described, steaming means, a steam pipe, a perforated shell surrounding said steam pipe and having an inlet for drying air, and a perforated drying drum on said shell adapted to receive drying air therefrom, said drum being ver-

tically adjustable, and means for holding the drum in different positions on the shell.

Signed at New York, in the county of New 10
York, and State of New York, this 18th day
of November A. D. 1927.

MAURICE M. KASANOF.
